SPACE HEATER

Raymond R. Dupler, 744 Euclid Ave.,
Toledo, Ohio 43605

Filed Apr. 1, 1971, Ser. No. 130,565

Term of patent 14 years

Int. Cl. D23—03

U.S. Cl. D23—93

FIG1

FIG2

FIG3

FIG. 1 is a front perspective view of the space heater, showing my new design;

FIG. 2 is a front elevational view thereof;

FIG. 3 is a side elevational view thereof.

I claim:

The ornamental design for a space heater, as shown.
